UNITED STATES PATENT OFFICE.

ANDREW H. BAKER, OF BROCKTON, MASSACHUSETTS, ASSIGNOR OF ONE-HALF TO OTIS F. CURTIS, OF BROCKTON, MASSACHUSETTS.

BOOT OR SHOE HOLDER.

SPECIFICATION forming part of Letters Patent No. 728,533, dated May 19, 1903.

Application filed July 11, 1902. Serial No. 115,147. (No model.)

To all whom it may concern:

Be it known that I, ANDREW H. BAKER, of Brockton, in the county of Plymouth and State of Massachusetts, have invented certain new and useful Improvements in Boot or Shoe Holders, of which the following is a specification.

This invention relates to a new and improved holder for boots and shoes.

Figure 1 is a perspective view showing a holder constructed in accordance with my invention. Fig. 2 is a longitudinal sectional view of the same. Fig. 3 is a detail view showing the arm swung to its inoperative position, the front portion of the foot-form being broken away. Fig. 4 is a cross-sectional view on the line 4-4 of Fig. 2, showing the flattening of the upper side of the rod and the engagement of the screw therewith. Fig. 5 is a side elevation showing the foot-form reversed from the position in which it appears in Fig. 1 in order to bring the sole of the shoe where it can be cleaned or manipulated.

1 represents a bracket adapted to be secured to the wall or other support in any desired way. This bracket is formed with lugs 2 and 3.

4 represents an arm formed at its rear end with a pintle 5, arranged in suitable apertures in the lugs 2 and 3. From the upper end of the pintle 5 the arm extends horizontally, as at 6, then downward, as at 7, then rearward, as at 8, and then forward, as at 9.

10 represents a foot-form provided with a longitudinal aperture 11 and a vertical aperture 12, communicating therewith. The aperture or hole 12 is preferably screw-threaded for the reception of the threads of the screw 13. The upper face of the part 9 is flattened, as at 14, in order that the end of the screw 13 may engage therewith and hold the form in longitudinal adjustment upon the part 9 and also prevent the form from turning on said part. The lug 3 is shown as formed with a notch 15, into which the part 6 of the arm 4 may drop in order to hold the arm against sidewise movement when the device is being used. When not in use, the part 6 is lifted out of the notch 15 and swung 50 around to the position shown in Fig. 3.

In practice the boot or shoe 20 is pulled upon the foot-form 10, the heel being pulled up over the part 8 of the arm 4, which is shown as having a curvature corresponding to that of the rear portion of the heel of the boot or shoe. The foot-form 10 is then pushed forward into the shoe and locked in place by means of the screw 13. Thereafter the shoe is cleaned and polished in the usual way.

In removing the shoe preferably the foot-form is loosened and slid back on the part 9.

In Fig. 5 is shown a method of employing my improved holder when it is desired to clean the soles of shoes. The foot-form is removed from the arm 4 and placed upon the pintle 5, and the part 9 is inserted in the lugs 2 and 3. This enables the form to be placed upon the part 5, so that the shoe can be placed thereon with the heel pointing downward.

It will be observed that the portions 8 and 7, respectively, of the arm are of such length and shape that they will bear against the inside of the counter and upper of a high-cut shoe at the rear thereof. By employing a fore part or foot-form having a higher instep portion than that shown in the drawings all portions of a high-cut shoe will be so supported that the ankle portions of the shoe may be effectively polished, as well as the vamp and instep.

In place of the flat part 14 on the rod I may provide the latter with a pin 21, arranged to slide in a suitable slot 22, communicating with the recess 11, as shown in Fig. 2.

The construction shown is exceedingly simple and inexpensive and meets all the requirements of a device of this sort.

Having thus explained the nature of my invention and described a way of making and using the same, although without attempting to set forth all of the forms in which it may be made or all of the modes of its use, what I claim, and desire to secure by Letters Patent, is—

1. A boot or shoe holder comprising a foot-form having a recess communicating with its rear face, a continuous bent rod formed as an arm adapted to enter said recess and having an integral part to conform to the interior of

the heel portion of the upper of a boot or shoe, and means for adjustably securing the form and arm together.

2. A boot or shoe holder comprising a foot-form having a recess communicating with its rear face, and a supporting-arm therefor comprising an integral member having angular ends, either one of said ends being constructed to be secured in the recess of the foot-form or to be fitted to a bracket, whereby the form may be supported with the sole portion or the instep portion uppermost.

3. A boot or shoe holder comprising a foot-form having a recess communicating with its rear face, and a supporting-arm therefor com-

prising an integral member having angular ends, either one of said ends being constructed to be secured in the recess of the foot-form or to be fitted to a bracket, whereby the form may be supported with the sole portion or the instep portion uppermost, means being provided for adjustably securing the foot-form relatively to the supporting-arm.

In testimony whereof I have affixed my signature in presence of two witnesses.

ANDREW H. BAKER.
